ANDREAS JAUMANN, OF BERLIN-CHARLOTTENBURG, GERMANY, ASSIGNOR TO SIEMENS & HALSKE, AKTIENGESELLSCHAFT, OF SIEMENSSTADT, NEAR BERLIN, GERMANY, A CORPORATION OF GERMANY

CONSTANT POTENTIAL DEVICE

Application filed February 27, 1929, Serial No. 342,991, and in Germany February 17, 1928.

For the smoothing of current supplied from direct current generators, rectifiers and similar sources of current which fail to furnish a pure direct current, but rather a kind 5 of direct current having, for instance, alternating current components superposed thereon, the use of a thermionic tube has been suggested whose internal resistance is so influenced by the source of current that 10 the potential fluctuations are eliminated. Along the line of this suggestion action is brought particularly by the fall of potential across a resistance which influences the grid of the tube. However, through the 15 control resistance there flows also the consuming or load current so that the suppression of the potential fluctuations is not insured in a perfect manner owing to the dependence on the load current.

20 According to the invention, the disturbances are eliminated independently of the load current, and for this purpose the control resistance is connected in a circuit in parallel relationship to the consumer apparatus. Also the tube arrangement is preferably included in this parallel branch, in 25 series with the control resistance. The fall of potential in the latter may influence the tube arrangement in various ways, as will 30 be seen from the following specification when read in connection with the accompanying drawings in which

Figure 1 shows the circuit arrangement of a constant potential device constructed in 35 accordance with my invention; while Figures 1A, 2 and 3 show modifications of the device of Figure 1.

Referring to the drawings, Figures 1 and 1A show a simple arrangement in which the 40 control resistance R is associated with the positive pole of the source of current and with the plate of thermionic tube A. The filament circuit of this tube is united with the negative pole of the source. In parallel relation with the resistance R is the primary winding of a transformer whose secondary winding is included in the grid circuit of the tube. As a rule, a negative biasing potential is required at the grid in order to insure 45 proper operation of the scheme, said bias-

ing potential being furnished from a battery 3. As the current through R grows there is produced a grid potential, with the result that the plate potential of the tube is varied. If the ratio of the transformer 55 is properly chosen, the variation in the plate potential will just compensate the variation of the fall of potential across resistance R, so that the potential across terminals 1, 2, with which the load resistance, for instance, 60 the plate circuit of tube arrangement is connected, preserves a constant value. In order that the superposed alternating current components may be properly suppressed, it will be desirable in many instances to keep the 65 direct current magnetization in the transformer as low as possible. For this purpose may be employed a third winding T on the transformer, as shown in Figure 1, one end of which is associated with the primary 70 winding and is brought by way of resistance r to the negative pole.

This circuit scheme operates properly inside a frequency range which depends upon the properties of the transformer. As a 75 general rule, in the presence of very low and very high frequencies, compensation will be inadequate. In this respect the scheme shown in Figure 2 operates more favorably.

Also in this arrangement, a control resistance R1 and a thermionic tube A are disposed in series between the terminals of the source of current. In parallel relation to the tube A is an auxiliary tube B in series with a resistance R2 which, as a general rule, 80 should be rather large. The fall of potential across resistance R1 directly controls the grid of tube B which, under certain circumstances may be united with the negative pole 85 of the source of current. At the plate of this tube B arise potential variations of opposite sign and larger amplitude, and these are fed through a grid battery to the grid of the main tube A. If, then, the current through the first tube grows and as a consequence the fall of potential across resistance R1, this is attended with a decrease of potential at the grid of the auxiliary tube. If the 90 value of resistance R2 is considerable (which it preferably should be) the plate current in 95 100

tube B does not change substantially, and there occurs a considerably greater positive potential variation at the plate of B and consequently also at the grid of tube A.

5 This potential variation may be so chosen that the potential at terminals 1, 2, for the load resistance remains constant.

The auxiliary tube serves essentially for electrostatic control and may therefore be 10 ordinarily quite small. The arrangement moreover, is predicated for its operation only on ohmic resistances so that it is practically independent of frequency.

Since the circuit arrangements herein- 15 before disclosed maintain a direct current potential across their terminals, while alternating current potentials or rapid fluctuations of potential of appreciable size are pre- cluded, they act similarly as a very large 20 condenser so that they could also be used in conjunction with choke-coils or low-pass filters for filtering out alternating current components.

A scheme of this kind is illustrated in 25 Figure 3, connected with the positive terminal of the source is a choke-coil D followed by a circuit arrangement which essentially is similar to the one shown in Figure 2. In lieu of the biasing potential battery between 30 the plate of tube B and the grid of tube A there is used here a condenser, and the grid of tube A is associated with the negative terminal of the source by way of a resistance W. The grid of tube B is united with a 35 point of control resistance R1, and then the biasing potential battery in the grid circuit of tube B may be dispensable.

The operation of the tube scheme shown in Figure 3 is fundamentally similar to Figure 2. However, what should also be kept in mind is that the current flows through 40 choke-coil D to the consumer which is united with terminals 1 and 2. Since the value of this current is not constant or invariable 45 once for ever, the potential will be a function of the load current even if the internal resistance of the source is negligible, because a fall of potential is set up across the direct current resistance of the choke-coil D. How- 50 ever, since the tube arrangement is designed to preserve a constant potential, it will pro- duce and result in a regulating current such that, in the presence of variable load, the fall 55 of potential across the choke-coil remains constant. As a result the operation of the tube arrangement may be unfavorably af- fected. However, it is possible to render it 60 independent of the load by the aid of a com- pensating resistance r' which, as a general rule, need have only a small value, and which, in the embodiment shown by way of example in Figure 3, may be connected be- 65 tween the control resistance R1 and the grid resistance W.

65 I claim:

1. An arrangement for smoothing out current to be applied from a pulsating direct current source to a load circuit including, a thermionic tube having an anode cathode and control electrode, a fixed impedance, means connecting the impedance of said tube and said fixed impedance in parallel with said load circuit, coupling means between said fixed impedance and said control electrode and amplifying means in said coupling means whereby variations in potential in said fixed impedance due to pulsations in said source are amplified and applied to the control electrode of said tube. 73

2. An arrangement for supplying direct current at constant potential from a pulsating direct current source to a load circuit including, a thermionic tube having anode cathode and control electrodes, a control resistance, a circuit connecting the impedance of said tube and said control resistance in parallel with the load circuit, an auxiliary thermionic tube having an anode, a cathode and a control electrode, a circuit connecting the anode cathode impedance of said last named tube in parallel with the anode cathode impedance of said first named tube, coupling means connected between said resistance and the control electrode of said last named tube, means connecting the anode of said last named tube to the control electrode of said first named tube, and a resistance connecting the control electrode of said first named tube to the negative terminal of said source. 78 80 90 95 100

3. In apparatus for smoothing out the potential of current obtained from a pulsating direct current source, a circuit including the anode and cathode impedance of a thermionic triode connected across the output terminals of said source, a series resistance in said circuit, an auxiliary triode, a circuit connecting the anode cathode impedance of said auxiliary tube in parallel to the anode cathode impedance of said main tube, a series resistance in said last mentioned circuit, a connection between the resistance in said first named circuit and the grid electrode of said auxiliary tube, a connection between the anode electrode of said auxiliary tube and the grid electrode of said main tube, and a condenser in said last named connection. 105 110 115

4. In radio apparatus adapted to supply constant potential from a pulsating direct current source to a load circuit connected across the terminals of said source, a circuit including a fixed impedance and a variable impedance connected in series across said source, impedance control means associated with said variable impedance, voltage amplifying means connecting said fixed impedance to said variable impedance, whereby potential variations in said fixed impedance due to pulsations in said source are 120 125 130

amplified and applied to said impedance varying means to regulate the impedance of said parallel circuit.

5. In means for supplying direct current at constant potential from a source of pulsating direct current to a load circuit, a fixed impedance, a thermionic tube having its anode cathode impedance connected in series with said fixed impedance across the terminals of said source, a transformer having its primary winding connected in parallel with said fixed impedance and its secondary winding connected to the control electrode of said thermionic tube whereby the potential variations in said fixed impedance are amplified and applied to the control electrode of said tube.

6. Means for supplying direct current at constant potential from a pulsating direct current source to a load circuit including a fixed impedance and a variable impedance connected in series across the terminals of said source, impedance control means associated with said variable impedance, a transformer having its primary winding connected in parallel with said fixed impedance and its secondary winding connected with said impedance control means, whereby potential variations in said fixed impedance, due to pulsations in said source, are amplified and applied to said impedance control means.

7. An arrangement, as claimed in claim 6, in which said transformer has a third winding connected in parallel with said variable impedance.

8. In means for supplying direct current at constant potential from a pulsating direct current source to a load circuit, a circuit including the anode and cathode impedance of a thermionic triode connected across the output terminals of said source, an impedance in series with said circuit, an auxiliary triode having its anode cathode impedance connected through a series impedance in parallel with the anode cathode impedance of said first named tube, means for connecting the control electrode cathode impedance of said last named tube in parallel with the series impedance of said first named circuit and a source of potential connecting the anode of said auxiliary tube to the control electrode of said first named tube.

ANDREAS JAUMANN.
